UNITED STATES PATENT OFFICE.

FÉLIX EMILE VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

TAKE-UP MOTION.

1,419,996.

Specification of Letters Patent. Patented June 20, 1922.

Application filed August 1, 1918. Serial No. 247,749.

To all whom it may concern:

Be it known that I, FÉLIX EMILE VALOIS, a citizen of the United States, residing at Haverhill, county of Essex, State of Massachusetts, have invented a certain new and useful Improvement in Take-Up Motions, of which the following is a specification, reference being had therein to the accompanying drawings.

This invention relates to take up mechanism for shoe sewing machines. One object of the invention is to provide a take up which can be operated without the use of grooved cams such as have heretofore been employed for this purpose. Another object is to provide mechanism which will produce the downward movement of the take-up during rotation of the main shaft through an arc of not more than about 60 degrees. Another object is to cause the take up to have a satisfactory upward movement.

The mechanism by means of which the take up is operated consists in general of a crank and connecting rod or pitman, the connecting rod being controlled by a link one end of which is pivoted to the connecting rod intermediate its ends and the other end of which has a pivotal point of connection, the position of which is varied in time with the rotation of the machine. As will be explained more in detail, this mechanism may be run at high speed and although the loop is pulled down during about one-sixth of the revolution of the main shaft, this part of the machine operates with perfect smoothness. There is more than one method by which the change in position of the point of connection of the controlling link may be varied in time with the machine. Two mechanisms for this purpose are described herein but the invention is not limited to the forms shown except as stated in the claims since it is intended to claim the invention in the broadest possible manner.

The invention will be fully understood from the following description when taken in connection with the accompanying drawings and the novel features thereof will be pointed out and clearly defined in the claims at the close of this specification.

In the drawings, Fig. 1 is a side elevation partly in section of a portion of a take-up mechanism and the related parts of a shoe sewing machine embodying the invention.

Fig. 2 is a front view of the parts shown in Fig. 1.

Fig. 3 is a view similar to Fig. 1 showing a modified form of the invention.

Fig. 4 is a view similar to Figs. 1 and 3 showing another modification of the invention.

Referring now to the drawings and particularly to Figs. 1 and 2 at 11 is shown the needle, at 12 the work table, at 13 the looper and at 14 the shuttle. The mechanism by means of which these and the other working instrumentalities of the sewing machine are given their proper motions is not shown in the present application as these have nothing to do with the herein-described invention. At 15 is shown the take up roll mounted on an arm 16. This arm is part of a rock shaft 17 oscillatably mounted on the frame 18. The highest position of the take up roll 15 is shown in Fig. 1 in dot and dash line, and the lowest position is shown in full line. As stated previously the driving mechanism which will now be described causes the take up roll to move from the highest position to the lowest position during a movement of the main shaft 19 through an arc of about 60 degrees. This movement is for the purpose of pulling down and setting the loop which has just passed over and around the shuttle.

At 20 is shown an arm on the rock shaft 17 to which is pivotally connected the link 21. The upper end of the link 21 is pivoted at 22 to the outer end of the triangular connecting rod or pitman 23, the other end being carried by the crank pin 24 of the crank 25 on the main shaft 19. The crank 25 rotates in the direction indicated by the arrow in Fig. 1. At 26 is shown a pair of controlling links, one end of which is pivotally connected at 27 to the connecting rod 23 at a point intermediate the crank pin 24 and the point of connection 22 with the link 21. The pivot 27 is also located at one side of the line between the crank pin 24 and the pivot 22. The other end of the controlling link 26 is caused to change its position in time with the movement of the main shaft. This is accomplished by means of a swinging link 28 pivoted to the controlling link 26 at the point 29 and at its other end to a pivot 30 mounted on a fixed part of the machine. At 31 is shown a transverse link which causes the pivot 29 to travel in the arc of a circle about the fixed

5 pivot 30. The link 31 is itself moved by a cam fork 32 pivoted at 33 on the frame of the machine and moved by an oscillating cam 34 on a rocker shaft 35. The rocker shaft 35 is caused to oscillate in time with the main shaft 19 by any suitable mechanism as for instance a crank 36 acting on a floating disk 49 surrounded by one end of a connecting rod 37 the other end of which is secured to an 10 arm 38 on the rocker shaft 35. Specific details of such mechanism are fully described in my co-pending application Ser. No. 247,753, filed August 1, 1918, to which application reference may be had for further disclosure of this feature of the invention.

20 In its operation the machine moves the take-up from the position shown in dot and dash lines to the position shown in full lines during a movement of the main shaft of about one-sixth of a revolution or 60 degrees. At the same time the cam fork 32 assumes the position shown in Fig. 1. This causes the pivot 29 to move in the arc of a circle about the fixed pivot 30 and causes the controlling link 26 to push down the connecting rod 23 very rapidly. This has the effect of moving the long link 21 and the take-up down with great rapidity as shown in Fig. 1.

30 In Fig. 3 is shown a modification of the hereindescribed improved take up operating mechanism. In this form of device, the rock shaft 17, link 21, connecting rod 23 and crank 25 are the same in general construction as in the form of mechanism shown in Figs. 35 1 and 2. At 40 is shown the controlling link one end of which is pivoted at 27 to the connecting rod 23 and the other end of which is pivoted to a pin 41 mounted on an eccentric 42 on a shaft 43. The shaft 43 extends through the hanger 44 and has on its other end an arm 45 which causes the eccentric shaft to oscillate. In the form shown in this figure, this link is connected to a connecting rod 46 which forms part of the 40 needle drive. By this arrangement, the arm 45 serves the double purpose of operating the eccentric 42 and controlling the position of the needle drive connecting rod 46. The operation of the mechanism shown in Fig. 50 3 is substantially the same as that shown in Figs. 1 and 2. The position of the pivot pin 41 for the controlling link 40 is shifted during the downward movement of the take up and greatly increases the rapidity of said 55 downward movement.

55 In Fig. 4 is shown a third form of mechanism embodying my invention. In this form, the triangular connecting rod 50 is acted upon by a controlling link 51, one end 60 of which has a stationary pivot 52, but the link which connects the connecting rod 50 with the rock shaft 53 of the take-up is made in two pieces 54 and 55 pivotally connected at 56. The pivot 56 is acted upon by a link 57 moved by the cam fork 58 and cam 59.

The effect of this mechanism is the same. The movement of the link 57 straightens suddenly the toggle joint formed by the two links 54 and 55 and thus gives the take-up 70 the quick movement required.

The three mechanisms shown and described herein are capable of being operated at high speed and when so operated run without noise or jar. This is due largely to the fact that the movement is produced 75 mainly by a crank and connecting rod instead of by a grooved cam and follower as heretofore. The mechanism described is simple and cheap to construct and wears well. In addition it is possible to produce a 80 more rapid downward movement of the take-up and still run the machine at high speed than has heretofore been possible where a cam has been used as with such mechanism the speed of movement of the take-up is 85 limited by the fact that the cam will pound if made too steep especially when the machine is run at high speed.

What I claim is:

1. In combination with a working instrumentality of a sewing machine, a crank, a connecting rod connected to said crank for actuation thereby, a connection joining the connecting rod and the working instrumentality, a controlling link one end of which is 90 connected to the connecting rod, and a cam moving in time with the machine, a cam follower operated by said cam and acting on the said controlling link to vary its position in time with the machine.

2. In combination with a take-up of a sewing machine, a rotary crank, a connecting rod, a connection joining the connecting rod and the take-up, a controlling link one end of which is connected to the connecting 105 rod, and means to vary the position of the other end of said controlling link.

3. In combination with the take-up of a sewing machine, a rock shaft on one arm of which the take-up is mounted and to the other arm of which is connected a link, a crank, a connecting rod, the free end of which is attached to said link, a controlling link one end of which is connected to the connecting rod, and means to vary the position of the other end of the controlling link in time with the movement of the machine.

4. In a machine of the class described, in combination, an oscillatable take-up and mechanism for actuating said take-up comprising a driving crank, a connecting rod or pitman pivotally connected to said crank, means for transmitting the motion of said connecting rod or pitman to said take-up, a second driving element, and means connecting said element with said rod or pitman for modifying the movement imparted thereto by said crank.

5. In a sewing machine, in combination, a movable take-up and mechanism for actuat-

- ing the same, said mechanism comprising a rotarilly driven crank provided with a crank pin, a connecting rod or pitman having one extremity pivoted upon said crank pin, 5 means connecting the opposite extremity of said rod or pitman to said take-up, and a second driving element operatively connected with said rod or pitman intermediate its ends for modifying the motion imparted to said 10 rod or pitman by said crank.
6. In a sewing machine, in combination, a movable take-up, a rotary driving member, a link interposed between said take-up and said rotary driving member, a rocker-member, 15 connecting means for imparting motion from said rocker-member to said take-up, and means independent of said connecting means for driving said rocker-member.
7. In a sewing machine, in combination, a 20 movable take-up, a rotary driving member, a link interposed between said take-up and
- said rotary driving member, a rocker-member, connecting means for imparting motion from said rocker-member to said link, and means independent of said connecting means 25 for driving said rocker-member.
8. In a sewing machine, in combination, a movable take-up, a rotary driving member, an oscillatory driving member, connecting means for driving said take-up from both of 30 said members, and means independent of said connecting means for moving said driving members.
9. In a sewing machine, in combination, a movable take-up, a crank, a rocker-shaft, 35 connecting means for driving said take-up simultaneously from said crank and rocker-shaft, and means independent of said connecting means for driving said rocker-shaft.

In testimony whereof I affix my signature. 40

FÉLIX EMILE VALOIS.
